UNITED STATES PATENT OFFICE

145,322

DESIGN FOR A TABLE MAT OR SIMILAR ARTICLE

Henry J. Muller, Lancaster, Pa.

Application March 18, 1946, Serial No. 127,640

Term of patent 3½ years

(Cl. D92—26)

To all whom it may concern:

Be it known that I, Henry J. Muller, a citizen of the United States, residing in Lancaster, county of Lancaster, and Commonwealth of Pennsylvania, have invented a new, original, and ornamental Design for a Table Mat or Similar Article, of which the following is a specification, reference being had to the accompanying drawing, forming a part thereof and in which the figure is a plan view of a table mat illustrating my design.

The dominant features of my design reside in the portion shown in solid lines.

I claim:

The ornamental design for a table mat or similar article, substantially as shown and described.

HENRY J. MULLER.
